UNITED STATES PATENT OFFICE.

AMBROSE N. DIEHL, OF DUQUESNE, AND FRANK E. LEAHY, OF MCKEESPORT,
PENNSYLVANIA.

APPARATUS FOR BURNING GASES.

1,392,921.

Specification of Letters Patent. Patented Oct. 11, 1921.

Application filed January 22, 1921. Serial No. 439,322.

To all whom it may concern:

Be it known that we, AMBROSE N. DIEHL and FRANK E. LEAHY, citizens of the United States, and residents, respectively, of Duquesne and McKeesport, both in the county of Allegheny and State of Pennsylvania, have invented certain new and useful Improvements in Apparatus for Burning Gases, of which the following is a specification.

This invention relates to the burning of gases, and more particularly to mechanism for regulating and controlling the relative amounts of air and gas supplied to the gas burner and also having means to control the draft from the burner so as to properly exhaust the products of combustion.

The invention is illustrated as applied to a battery of steam boilers utilizing blast furnace gas for fuel, although it will be understood that this invention may be used with all fuel gases.

The principal object of our invention is to provide improved means for securing the correct amount of air for the volume of gas flowing through the burner, and also to automatically control the draft drawing the products of combustion away from the burner.

Another object of the invention is to provide suitable automatic apparatus for controlling the inflow of air to the burner and outflow of the products of combustion.

Still another object of this invention is to combine the improved and novel apparatus in such manner so that the gas entering the burner will be mixed with air in suitable proportions to get the maximum heat therefrom at all times.

With these and other objects in view, our invention as applied to a battery of steam boilers is illustrated in the accompanying drawings, in which—

Figure 1 is an end elevation of a battery of boilers having our invention applied thereto.

Fig. 2 is a somewhat diagrammatic elevation of the control apparatus on a larger scale.

Fig. 3 is a sectional elevation of the regulator.

Fig. 4 is a sectional view of the lever balance valve.

Referring particularly to the drawings, the letter A designates the boiler house gen-

erally, which houses the battery of boilers 2, each of which has one or more gas burners 3 passing through its forward wall for supplying heat to the boilers. The burners for each boiler receive their gas supply from suitable manifolds 4 connected by a branch main 6 to the gas supply main 7. The branch main 6 is provided with a suitable hand operated butter-fly valve 6' to control the flow of gas to the manifold 4.

The burners 3 for each boiler are provided with a forced draft or air supply by a turbo-driven fan 8 connected by main 9 to an air manifold 10 which supplies air to the burners through suitable branches 11 leading from the air manifold into the mixing chamber of the burner.

The induced draft to carry away the products of combustion is formed by a second turbo-driven fan 12 communicating with the boiler flues in a well known manner and exhausting through a flue or stack 13.

The turbo-driven fans 8 and 12 are each supplied with steam from the boilers 2 through a branch steam main 14 having branches 15 and 16 leading to the turbos and provided with suitable throttle valves 17 and 18 respectively.

Our invention pertains principally to the control of the steam entering the branch main 14 by means of a lever balance valve 20 which is in turn controlled by the gas pressure in the gas manifold 4.

The gas pressure from the manifold, which is proportional to the flow of gas through the burners, is applied through a suitable large diameter main 22 having a small diameter branch 23 to an incremental type of regulator X which operates the valve 20.

The regulator X comprises a casing 25 having a pressure operated diaphragm 26 mounted therein provided with a plunger rod 27 which extends downwardly through a pilot valve 32 and has its lower end pivotally secured to the short end of a fulcrumed lever arm 29, the other end of which carries a sliding weight 30. A suitable fluid pressure cylinder 31 adapted to control the movement of the sliding weight 30 is also provided in the regulator, and fluid under pressure is admitted to the cylinder through the pilot valve 32 which is operated by the plunger rod 27.

The fluid pressure cylinder 31 has a dou-

ble acting piston 34 mounted therein, having a piston rod 35 which extends through the stuffing box 36 and gland 37 on one head of the cylinder. The outer end of the piston rod is connected by a flexible connection such as chain 39 to a variable angular transmission wheel 40 which is mounted on a suitable standard 41.

10 The piston rod is also connected by a pivoted link 38 to the sliding weight 30 so as to cause said weight to move along the lever 29 as said piston rod is reciprocated.

15 The cylinder 31 is provided with a port 42 opening into the cylinder at one end thereof and extending longitudinally through the cylinder side wall. The pilot valve 32 is secured directly to the forward end of the cylinder 31 and has ports 48 in communication with port 42 in the cylinder and a second port 49 opening directly into the cylinder.

20 The pilot valve 32 is a four-way valve having an inlet port 50, which may be connected by suitable piping to a source of fluid pressure, and an outlet port 51 which may be connected by suitable piping to a drain or waste conduit.

25 The pilot valve 32 is provided at each end with a stuffing box 56 and gland 57, through which the plunger rod 27 reciprocates. In the particular pilot valve construction shown, the chamber for the piston is provided with a bushing 59 having two series of transverse openings or holes 60 and 61 therein, communicating with the fluid pressure ports 48 and 49 of the valve. The plunger rod 27 serves as a piston rod for the valve 32, and disks 62 and 63 are secured thereon to form a double piston. The 30 disks 62 and 63 are arranged to move into and out of position to close the openings 60 and 61 in the bushing 59. The inlet port 50 of the valve opens into the upper end of the valve chamber. The space in the 35 valve chamber above the disk 62 is connected by a discharge passage 65 with the space below the disk 63, the arrangement being such that when the disks are moved downwardly by the depression of diaphragm 50 the valve inlet 50 will be connected to the fluid pressure cylinder through port 49 while the valve outlet port 51 will be connected to the port 42 by port 48 and when the valve piston is moved upwardly, the 55 ports will be oppositely connected so as to admit water or other fluid pressure to the cylinder on the other side of the piston 34 and cause the piston to move in the opposite direction within the fluid pressure cylinder. 60 Preferably water will be the fluid used in the cylinder, although an elastic fluid may be employed when necessary or desirable.

The lever balance valve 20 comprises a casing 68 having an inlet chamber 69 formed

therein and provided with upper and lower 65 inlets 70 and 71 controlled by a double, vertically operating lever piston valve having heads 72 and 73 adapted to seat in the respective inlets 70 and 71. The inlets 70 and 71 open into the body of the valve which 70 forms an outlet chamber 74. The inlet and outlet chambers 69 and 74, respectively, are connected with the branch steam main 14 as will be obvious.

75 A head 75 is formed on the upper portion of the valve casing to provide for the lever operating mechanism. A crank lever 76 is journaled in the head 75 and has its arm pivotally connected to a link 77 which has its lower end pivotally connected to the piston valve. An operating lever 78 is rigidly mounted intermediate its ends on the other arm of the crank 76 and is provided with a suitable counterweight 79 at its rear end. Vertical movement of the lever 78 will rotate the crank lever 76 and due to the link connection between said crank and the valve will move said valve vertically to either open or close the inlets 70 and 71.

90 The lever 78 is adapted to be operated indirectly by the piston rod 35 of the hydraulic cylinder 31, through the annular transmission wheel 40 which is connected to the lever 78 by a flexible member 80. The angular transmission wheel 40 is provided with a radial 95 rod and the flexible member 80 is secured by one end of this rod and passes upwardly over an idler pulley 81 and has its other end secured to the lever 78. The wheel 40 is also provided with a counterweight 82 100 secured thereto by a flexible member 83 to provide means for revolving the wheel.

105 The idler pulley 81 is located a considerable distance to one side of the vertical axis of the angular transmission wheel 40 to provide the necessary angularity which gives a wide range of variation in the operation of the valve 20.

The operation of the device is as follows:

110 The device being assembled and in operation, a pressure corresponding to the flow of gas entering the gas manifold 4 from the main 7, is communicated to the diaphragm 26 of the regulator 25 through pipes or mains 22 and 23. An increase in pressure 115 will depress the diaphragm and move the plunger 27 downwardly, thereby opening the pilot valve 32 and throwing the lever 29 out of equilibrium. As the pilot valve is 120 opened fluid will enter through the inlet 49 of the valve thereby forcing the piston 34 and piston rod 35 in the cylinder 31, outwardly, and drawing weight 30 outwardly along the weight lever 29. The 125 outward movement of the piston rod 35 will be communicated through the flexible member 39 to the transmission wheel 40 and therefore the counterweight 82 will move

said wheel clockwise and allow the flexible member 80 to move upwardly, permitting the counterweight 79 to exert enough force upon the lever 78 to rock it and thereby open the valve 20 and allowing more steam to flow through the branch mains 15 and 16 to the turbo-fans 8 and 12.

This increase in the steam supply will increase the speed of both fans 8 and 12, thereby increasing the volume of air supplied to the burner 3 for combustion and increasing the amount of the products of combustion exhausted through the stack.

The piston rod 35, in moving outwardly, will move the weight 30 outwardly along the weight lever 29 due to the link connection 38. When the weight reaches the point on the lever 29 where it will counterbalance the gas pressure, it will overbalance the lever 29, thus pushing up the plunger 27 which will in turn press upon and move upwardly into its normal position, thereby closing the pilot valve 32.

When the gas pressure decreases the weight 30 will further overbalance the lever 29, thus moving the plunger 27 upward still further, pushing up the diaphragm 26 above its normal position and opening the pilot valve 32 so as to admit fluid under pressure through the port 48 into the passage-way 42 in the cylinder and opening port 49, thereby allowing the fluid in the rear of the piston 34 to exhaust and other fluid to enter in front of the piston and move it rearwardly to its normal position. As the piston 34 returns to normal position it will return the weight 30 to its normal position, and also will exert power on the transmission wheel 40 through the flexible member 39, thereby revolving said wheel so as to take up the flexible member 80, rock the lever 78 and thereby close the valve 20. Closing movement of the valve 20 will decrease the steam supply to the turbo fans 8 and 12, thereby reducing the capacity of these fans during the lack of gas pressure.

As the piston rod 35 moves inwardly, as has been said, the weight is moved along the rod 29. When the weight reaches such a point as to balance the gas pressure on the diaphragm, the diaphragm will return to normal, thus forcing down plunger 27 and closing the pilot valve 32. The closing movement of the pilot valve 32 will cause the valve 20 to remain stationary until the gas pressure again fluctuates, when the diaphragm 26 will again move upwardly or downwardly according to whether the gas pressure is decreased or increased.

Each movement of the diaphragm 26 will be communicated by the plunger 27 to the pilot valve 32 and cause one of the cycle of operations above described.

We claim:

1. The combination with a gas burner hav-

ing separate turbo-fans for supplying air for combustion and for withdrawing the products of combustion, of means operated by the pressure of the gas supplied to said burner for regulating the speed of both of said fans, so as to provide the correct amount of air for combustion and the correct draft for the different gas pressures.

2. The combination with a gas manifold and burner, separate turbo-fans for supplying air to said burner for combustion and for withdrawing the products of combustion, and a single steam main for supplying steam from said boiler to said fans, of means operated by the pressure of the gas in said manifold for regulating the speed of both of said fans, said means comprising a diaphragm adapted to be operated by the gas, a pressure control valve in said steam main, and means controlled by the movements of said diaphragm for operating said control valve.

3. The combination with a gas fired boiler having a gas manifold and burner, separate turbo-fans for supplying air to said burner for combustion, and for withdrawing the products of combustion, and a single steam main for supplying steam from said boiler to said fans, of means operated by the pressure of the gas in said manifold for regulating the speed of both of said fans, said means comprising a control valve in said steam main, and an incremental type of regulator adapted to operate said control valve, said regulator being actuated by the pressure of the gas in said gas manifold.

4. The combination with a gas fired boiler having a gas manifold and burner, separate turbo-fans for supplying air to said burner for combustion and for withdrawing the products of combustion, and a single steam main for supplying steam from said boiler to said fans, of means operated by the pressure of the gas in said manifold for regulating the speed of both of said fans, said means comprising a control valve in said steam main, a variable angular transmission wheel connected to said valve and adapted to operate the same, and an incremental type of regulator adapted to operate said angular transmission wheel, said regulator being actuated by the pressure of the gas in said gas manifold.

5. The combination with a gas fired boiler having a gas manifold and burner, an air manifold for supplying air to the burner, a stack for the products of combustion, a turbo-fan for supplying air to said air manifold, a second turbo-fan for drawing the products of combustion through said stack, and a single steam main from said boiler for supplying to both of said fans, of a control valve in said steam main, a variable angular transmission wheel having a flexible connection with said valve and adapted

to operate the same, and an incremental type of regulator being actuated by the pressure of gas in said gas manifold.

6. The combination with a gas burner of 5 a turbo-fan for supplying air to support combustion, and means operated by the pressure of gas supplied to said burner for regu-

lating the speed of said fan so as to provide the correct volume of air to support efficient combustion at different gas pressures.

In testimony whereof we have hereunto signed our names.

AMBROSE N. DIEHL.
FRANK E. LEAHY.
